(57) **CLAIM**

The ornamental design for an electric hair clipper, as shown and described.

DESCRIPTION

FIG. 1 is a perspective view of an electric hair clipper showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective schematic view illustrating an application of an electric hair clipper showing my design.

The broken lines shown in the drawings represent the environment and form no part of the claimed design.
